VEHICLE BODY CONSTRUCTION

Filed May 9, 1928

ERWIN L. BARE. *ATTORNEY*

UNITED STATES PATENT OFFICE

ERWIN L. BARE, OF DETROIT, MICHIGAN, ASSIGNOR TO THE MURRAY CORPORATION
OF AMERICA, A CORPORATION OF DELAWARE

VEHICLE BODY CONSTRUCTION

Application filed May 9, 1928. Serial No. 276,272.

One object of my invention is to provide an economically constructed and strong header and roof support for a closed vehicle body.

Another object of my invention is to provide a metallic header and roof support for closed vehicle bodies which are particularly adapted to use in connection with other frame members of wood.

With these and other objects in view, my invention consists in the arrangement, combination and construction of the various parts of my improved device, as described in the specification, claimed in my claims and shown in the accompanying drawings, in which:

15 Fig. 1 is a perspective of my header and roof support secured to metal forward pillars.

Fig. 2 is a perspective of my header and roof supporting member showing the application of wood header members and roof rail thereto.

Fig. 3 is a plan view of my header and roof supporting member, also showing the application of wood members.

25 Fig. 4 is a view taken on the line 4—4 of Fig. 3.

I have shown a front frame member for a vehicle body comprising the forward upright metal body pillars 10 and 11 and cowl bar 12.

30 A metal header member and roof support 13 is secured to the upper ends of the pillars. The pillars 10 and 11 are secured to the wood sill members 16 by brace members 15. The braces 25 and 26 are suitably secured to pillars 10 and 11 and extend forwardly and their free ends are adapted to be secured to the dash panel of the vehicle body which is not shown, and which will rest on the forward ends of the sills 16.

40 It will be understood that the pillar members shown and described herein are not of my invention but are the subject of a pending application filed by Marvin W. Moesta, Serial No. 276,263, filed May 9, 1928.

45 The header member 13 rests upon inwardly extending horizontal lugs 33 formed on the upper ends of the pillars 10 and 11 and is secured thereto by rivets or welding. Rearward extensions 35 of angle shape are formed

50 on the ends of the header 13 and are adapted

to receive and support the forward ends of wood roof rail members 50 which may be secured thereto by bolts 51 and screws 52, or other suitable means. The rear sides 30 of the pillars 10 and 11 are extended and rearwardly bent to form supporting flanges 34 upon which extensions 35 rest and to which they are secured by welding or other suitable means. The header member 13 has a forwardly extending horizontal flange 36 at its lower edge, and the central portion of the header 13, in which an intermediate vertical web 14 is considerably wider than the end portions, has a short forwardly extending horizontal flange 37 in its upper edge. A notch 38 may be formed in the lower side of the wide portion of the header 13 to accommodate windshield operating mechanism which is not shown.

55 A triangular web portion 39 connects the upper edges of the extensions 35 and the upper edges of the end portions of the header 13 as shown in Figure 3. This web 39 is rounded and inclined downwardly toward the tops of the pillars 10 and 11, as shown at the right in Figure 1, in order that the forward ends of the purline roof members 40 may rest thereon and be secured thereto by screws or bolts and extend thereover and be mortised in the wooden header piece 47.

60 Wooden header pieces 45 and 47 are supported by the member 13 and fit between the flanges 36 and 37 and are secured to the member 13 by screws or other suitable means (not shown) inserted from the rear through apertures 46 in the member 13 into the rear sides of the members 45 and 47. The wood member 47 extends forwardly and overhangs the member 45 and has its upper surface curved to conform to the line of the roof. The wood header members 45 and 47, only a straight central portion of member 47 being engaged by the short flange 37, may serve as tacking strips to which metal molding and the roof covering may be attached and also as strengthening members for the header.

65 I have provided a forward header and roof support for closed vehicle bodies which effectively and securely ties the forward ends of the roof members and the forward pillar

members together and which is particularly adapted to use in connection with metal pillars and wood frame members for the roof.

It will be obvious that various changes 5 may be made in the arrangement, combination and construction of the various parts of my improved device without departing from the spirit of my invention, and it is my intention to cover by my claims such changes 10 as may be reasonably included within the scope thereof.

What I claim is:

1. In automobile body construction, in combination with a pair of upright forward metal 15 pillars, a metal bar of channel shape in its intermediate portions extending between and secured to the upper ends of said pillars, wood header bars secured to and supported by said metal bar and extending over the length 20 thereof, angle shaped extensions integrally secured to the ends of said metal bar and extending rearwardly from the upper ends of said pillars, and wood roof rails having their forward portions supported by and secured 25 to said angle shaped extensions and having their forward ends joined to the ends of said wood header member.

2. In automobile body construction, in combination with a pair of upright forward 30 metal pillars, a metal bar extending between and secured to the upper ends of said pillars, having a lateral forwardly extending flange on its lower edge, having its intermediate web portion of greater width than its end portions 35 and having a forwardly extending lateral flange on the upper edge of said wide web portion, angle shaped roof rail supports integrally joined to the ends of said bar and extending rearwardly from the upper ends of 40 said pillars, and having inclined integral webs joining the adjacent upper edges of said bar and said extensions and forming supports for the forward portions of purline roof members, and wood header members secured to 45 said metal bar between the forwardly extending flanges thereof.

3. In automobile body construction, the combination of a pair of upright metal forward pillars of angular cross section having 50 the top portions thereof split longitudinally and the sides bent and extended one transversely and the other rearwardly with respect to the body, a header member formed of a single metal stamping of angular cross section extending between said pillars and resting upon and secured to said transverse pillar flanges, and having integral rearwardly directed end extensions of angular cross section resting upon and secured to said rearwardly 55 extending pillar flanges, the open side of the angular header being presented outwardly and upwardly and adapted to receive and support wood roof rails and header strip.

4. In automobile body construction, in 60 combination with a pair of forward upright

metal pillars, a metal bar disposed horizontally between and secured to the upper ends of said pillars and having a vertically disposed web portion and forwardly extending lateral flanges formed on the upper and lower edges of said web portion, the upper flange being centrally positioned and shorter than the lower flange, angle shaped extensions formed integrally on the ends of said bar and extending rearwardly from the ends of said bar and said pillars, all for supporting roof frame members.

5. In automobile body construction, in combination with a pair of upright forward metal pillars, a metal bar extending between and secured to the upper ends of said pillars, having a lateral forwardly extending flange on its lower edge, having an intermediate vertical web portion of greater width than its end portions and having a forwardly extending lateral flange on the upper edge of said wide web portion, and angle shaped roof rail supports integrally formed on the ends of said bar and extending rearwardly from the upper ends of said pillars, a wood header member coextensive with and secured to said header bar, and roof rails secured both to said angle shaped supports and to said wood header member.
